UNITED STATES PATENT OFFICE

2,420,401

CENTRIFUGAL PUMP

Ivan M. Prokofieff, Staten Island, N. Y.

Application June 8, 1945, Serial No. 598,341

4 Claims. (Cl. 103—103)

1

This invention relates to improvements in centrifugal pumps.

One of the objects of this invention is to produce a centrifugal pump of high hydraulic efficiency at a minimum cost of construction.

Another object of my invention is to produce a centrifugal pump of high hydraulic efficiency in which the cost of operation will be minimized.

Another object of my invention is to produce a centrifugal pump fabricated from a series of separate parts, preferably composed of cold-rolled metal strips or plates, connected or joined to adjacent strips or plates or to other members to provide a complete pump.

To secure a maximum of hydraulic efficiency three factors are of great importance: (1) the elimination of jolts in the mass of passing liquid caused by bulges and inaccurate curvature of the vanes of the impeller and of the volute wall of the casing; (2) the reduction of friction of the flowing liquid upon the surfaces of the impeller vanes and upon the surface of the volute wall of the casing by providing finished surfaces and the perfecting of such surfaces to a maximum degree; and (3) minimizing the amount of eddy currents in the flow of liquid at the points of diversion of such flow and at the points of changes in the velocities and minimizing of impacts between such currents and the surfaces of the impeller vanes and volute wall of the casing.

In regard to the factor first mentioned, it will be understood that every bulge or inaccuracy of the curvature of the impeller vanes and of the casings produces, in operation, a jolt of a part of the mass of passing liquid. Such jolts absorb mechanical energy without any beneficial effect to the hydraulic performance at the discharge and a tremendous number of such jolts will absorb a considerable portion of such mechanical energy without beneficial effect.

The second factor requires mathematically correct curvatures and the elimination of any imperfections in such surfaces, while in regard to the third factor, there is only one point to be considered, that is the discharge. My discharge arrangement consists of a discharge chamber having the shape of a segment of a circle and one end of the wall of this segmental discharge chamber is a continuation of the volute wall at the discharge side. In regard to the third factor, there is only one point to be considered and that is the method of discharge to avoid the eddy currents and impacts referred to.

With these and other objects in view, the invention comprises the combination of members

2

and arrangement of parts so combined as to coact and cooperate with each other in the performance of the functions and the accomplishment of the results herein contemplated, and comprises in one of its adaptations the species or preferred form illustrated in the accompanying drawings, in which—

Fig. 1 is a view in perspective of the peripheral wall of the casing combined with the discharge chamber;

Fig. 2 is a section through the pump parallel to the bottom substantially on the line 2—2 of Fig. 3, looking in the direction of the arrows;

Fig. 3 is a cross-section of the pump along the impeller shaft substantially on the line 3—3 of Fig. 2;

Fig. 4 is a view in plan of a modified form of impeller vane; and

Fig. 5 is a view of an impeller vane similar to that shown in Fig. 2 embodying a hub member for the impeller shaft.

Referring now to these drawings, which illustrate a preferred embodiment of my invention, I employ for the construction both of the impeller and of the volute-casing cold rolled metal sheets, plates or strips and bend such sheets or plates of metal on templates to the mathematically correct curve. The use of such sheets, strips or plates of cold rolled metal enables the bending to be accomplished by conventional means and comprises a simple matter as it is a very simple matter to bend such a strip on a template, and obviously by providing a suitable template the mathematically correct curve for such cold rolled metal sheets, plates or strips may be obtained, and I am thus enabled to totally eliminate any possibility of bulges or inaccuracies of the curve and to solve all the problems referred to as factors numbered 1 and 2. Obviously the various connections or joints between the edges of the impeller vanes with the discs and at the hub and the connections or joints between the volute wall of the casing and the circular wall of the discharge chamber may be accomplished in any conventional manner that will not leave bulges and will enable the correct positioning of the vanes of the impeller in relation to the discs thereof, as well as the positioning of the end of the volute wall of the casting and the end of the wall of the discharge chamber.

I have found that by adopting this method of construction, the hydraulic efficiency of my pump will rise as high as 90 to 95% as against 50 to 75% of conventionally-constructed cast-metal pumps

and the cost of construction will be reduced to as low as 10% to 15% of such cast metal pumps, thus providing a saving or economy of 85% to 90% of such cost. This saving is primarily due to the elimination of all the work of pattern-making, molding, core-making, casting, machining, hand-finishing, etc.

The above statement of efficiency and saving in the cost of manufacture has been definitely proven by manufacture and the use of working models of a small capacity pump of about one H. P., and there is no doubt that the same or even better degrees of efficiency and savings may be accomplished in the manufacture of huge pumps for dredging, irrigation, dry docks, locks, etc.

Furthermore, there is no doubt that this method of construction in the same small scale of my one H. P. pump may be beneficially adapted for sections of multiple stage high pressure pumps of all sizes.

As to the third factor hereinabove referred to, the only point to be considered is the discharge. My proposed discharge construction consists of a discharge chamber having a wall of the shape of a segment of a circle; one end of this segment of a circle merges with and comprises a continuation of the volute wall at the discharge side and the other end is connected with the volute casing at the very beginning of the curve at a very small angle. In this way the volute casing and the periphery of the discharge chamber will constitute one uninterrupted body.

Referring specifically to these drawings, 1 indicates the pump casing and 2 is the discharge chamber. As shown, the end wall 3 of the discharge chamber comprises a segmental part of a circle which is continuous and merges with a peripheral volute-curved casing wall 4, and this volute-curved wall-portion 4 extends to the connection or joint 5 between the said casing wall and the wall 3 of the discharge chamber. This connection 5 is positioned at the very beginning of the volute curve and the two walls extend from each other at a very small angle. In this way the peripheral volute-casing wall and the peripheral wall of the discharge chamber comprises a single uninterrupted and merged body. An impeller 6 is shown in Fig. 4 which comprises a pair of identical discs 7 and 8 and four identical vanes 9 which are, as aforesaid, bent into the proper curvature and each of the same has its inner hub end 10 abutting each other to provide a hub 11 of polygonic or square configuration. The vanes 9 are suitably connected to the discs 7 and 8 and to each other at 10 to form the polygonic hub 11 which is mounted upon a shaft 12 with a square end 13 that fits into and loosely engages with the square polygonic hub 11. The shaft 12 is mounted in a shaft holding block 14 with a stuffing box 15 and the impeller and casing are mounted between side plates 16 and 17 and held in place by supplemental side plates 18 and 19. The impeller side-plate 17 is provided with an in-take aperture or hole 20 registering with an axially disposed intake hole 21 in the impeller disc 8. A base plate 22 is likewise provided with a hole 23 registering with the intake holes 20 and 21.

In the embodiment shown, spacing washers 24 and 25 are positioned between the side plates and the discs 7 and 8 and, in the preferred form of my invention, the washer 25 is composed of rubber or like elastic material. The side plate 16 is provided with a circular discharge hole 26 registering with the discharge chamber 2 and

a fixture or conduit 27 is fitted into the discharge hole 26.

In Fig. 4 I have shown a modified form of impeller vanes in which three vanes 9 are connected to each other at 10' to form a polygonal hub 11'.

In Fig. 5 I have shown another form of impeller vanes 9, the number and curvature of which are in all respects similar to those shown in Fig. 2.

- 10 The vanes 9 in Fig. 5, however, are fastened at their inner ends to each other and to a square hub member 28 provided with a hub aperture 28' within which the square end 13 of the shaft 12 is adapted to fit. In other respects the vanes shown in Fig. 5 are similar to those illustrated in Fig. 2.
- 15 By utilizing side or closure plates, each composed of two layers of abutting flat plates, I produce a construction in which each of the inner members 18 and 19 of the flat side plates may have an opening or hole cut therein whose peripheral line is identical to the line of the peripheral wall of the volute housing for the impeller and discharge-chamber housing, and the 20 combined volute housing-wall and discharge-chamber housing-wall will fit into these opposed openings to provide a facile method of assembly as well as an edge reinforcement for said wall of said impeller and discharge-chamber housings. 25 The side plates 16 and 17 abut and are securely fastened to the plates 18 and 19 and form closure plates for the said sidewall of the impeller-housing and discharge-chamber. The bottom closure plate 17 is provided with the inlet opening 20 while the upper closure plate 16 is provided with the circular outlet opening 26. As 30 illustrated, the base plate also comprises a flat plate 22 which abuts the bottom closure plate 17. A base plate is desirable in embodiments of 35 my invention for certain installations, but is not essential.

Having described my invention, I claim:

1. A centrifugal pump embodying, in combination, a pump casing having a housing composed 45 of an impeller housing portion and a discharge chamber portion, said impeller housing portion having a volute-curved side wall and said discharge chamber portion having a side wall of arcuate conformation, an impeller mounted for 50 rotation within said impeller housing portion, said two housing portions communicating with each other in the direction of flow from said impeller through a gradually expanding channel, and said side wall portions being formed integrally of one 55 continuously curved imperforate strip of sheet metal having its opposite ends fastened together to provide a discharge chamber completely closed in said direction of flow from said impeller, and flat closure members at opposite ends of the 60 entire side wall, one of which members is provided with an inlet opening at a position registering with said volute impeller housing portion and the other is provided with an outlet opening at a position registering with said discharge-chamber housing portion.

2. A centrifugal pump embodying, in combination, a pump casing having a housing composed 65 of an impeller housing portion and a discharge chamber portion, said impeller housing portion having a volute-curved side wall and said discharge chamber portion having a side wall of arcuate conformation, an impeller mounted for 70 rotation within said impeller housing portion, said two housing portions communicating with each other in the direction of flow from said impeller

through a gradually expanding channel, and said side wall portions being formed integrally of one continuously curved imperforate strip of sheet metal having its opposite ends fastened together to provide a discharge chamber completely closed in said direction of flow from said impeller, and flat closure members at opposite ends of the entire side wall, one of which members is provided with an inlet opening at a position registering with said volute impeller housing portion and the other is provided with an outlet opening at a position registering with said discharge-chamber housing portion, said closure members each being composed of outer and inner layers of abutting flat plates, the inner layer having an opening therein whose peripheral line is identiacal to the line of the periphery of the volute housing and discharge-chamber housing.

3. A centrifugal pump as claimed in claim 2 in which a circular discharge-opening is formed in the upper layer of the upper closure plates, said discharge opening being located in axial alignment with the arcuate side wall of the discharge-chamber and having a discharge fitting inserted therein and extending perpendicularly to the said upper layer of closure plates.

4. A centrifugal pump embodying, in combination, a pump casing having a housing composed of an impeller housing portion and a discharge chamber portion, said impeller housing portion having a volutely curved side wall and said discharge chamber portion having a side wall of arcuate conformation, an impeller mounted for rotation within said impeller housing portion, said two

housing portions communicating with each other in the direction of flow from said impeller through a gradually expanding channel, and said side wall portions being formed integrally of one continuously curved imperforate strip of sheet metal having its opposite ends fastened together to provide a discharge chamber completely closed in said direction of flow from said impeller, and flat closure members at opposite ends of the entire side wall, one of which members is provided with an inlet opening at a position registering with said volute impeller housing portion and the other is provided with an outlet opening at a position registering with said discharge-chamber housing portion, said volutely curved impeller housing portion beginning at a point closely adjacent to the circumferential periphery of said impeller at one side thereof and gradually expanding as it extends completely around said impeller and merging at the opposite side of said impeller with said discharge casing portion.
